UNITED STATES PATENT OFFICE.

FRED A. FISHBAUGH, OF LONDON, OHIO.

BELT-STRETCHING MECHANISM.

1,358,433.

Specification of Letters Patent. Patented Nov. 9, 1920.

Application filed April 3, 1919. Serial No. 287,314.

To all whom it may concern:

Be it known that FRED A. FISHBAUGH, a citizen of the United States, residing at London, in the county of Madison and State of Ohio, has invented certain new and useful Improvements in Belt-Stretching Mechanism, of which the following is a specification.

This invention relates to belt stretching mechanism, and has for its primary object to provide novel and efficient mechanism for drawing the ends of a driving belt into contiguous relation so that they may be securely laced together.

15 A main object of the invention is to provide mechanism of the aforesaid character which may be quickly and securely connected to the ends of a belt, and includes a plurality of frames capable of being easily 20 and quickly secured to the ends of a driving belt in order that the latter will be securely confined within said frames, and to provide adjusting mechanism in connection with said frames which is capable of drawing the 25 latter relatively in order that the ends of the belt may be placed in adjacent relation.

Another object of the invention resides in constructing the frames to include dovetail sockets for the reception of similarly 30 shaped clamping blocks, which serve when pressure is applied to the frames to securely grip the ends of a belt therein, and to provide a plurality of cam levers capable of engaging with said blocks to press the 35 latter into their recesses or sockets and into securely bound relation with said belt, the cam levers being capable of being quickly operated and to exert the required pressure upon said blocks to prevent undue movement of the latter.

40 A further object of the invention resides in equipping the clamping blocks with sets of relatively thin metallic wear plates, each set of which having a common pivot, where- 45 by said plates may be selectively positioned upon the blocks in such manner as to receive the wear of the cam levers when the latter are operated to assume locking positions. This construction enables the blocks 50 to be relieved of the wear caused by the operation of the levers, and also, serves to permit the levers to exercise their maximum

binding action upon the blocks irrespective of varying belt thicknesses.

With these and other objects in view, as 55 will appear as the description proceeds, the invention accordingly consists in the novel features of construction, combination and arrangement of elements hereinafter more 60 fully described and having the scope there- of pointed out in the appended claims.

In the accompanying drawing, forming 65 a part of this specification, and in which similar characters of reference denote like and corresponding parts:

Figure 1 is a top plan view of the improved belt stretching mechanism comprising the present invention,

Fig. 2 is an end elevation thereof, and

Fig. 3 is a transverse sectional view taken 70 along the line 3-3 of Fig. 1.

Fig. 4 is a detail vertical sectional view taken along the line 4-4 of Fig. 2.

Referring more particularly to the details of the invention, the belt stretcher A in its 75 preferred form consists of a pair of frames 1 and 2 which are employed to be connected with the adjoining ends of a belt 3, in order that said ends may be drawn together to effect their lacing. To this end the frames 80 are provided with oppositely situated dovetailed recesses 4 in which the ends of the belt 3 are positioned and these ends are clamped into engagement with the frames by means of blocks 5, which are shaped to 85 conform with the dovetailed configuration of the recesses 4 and are adapted to rest upon the ends of said belt and completely occupy the recesses 4, so that the upper surfaces of said blocks are substantially flush 90 with those of the frames 1 and 2. To lock the blocks within said recesses and to force the same into firm frictional relation with the ends of the belt 3, use is made of a plurality of pivoted cam levers 6, which are 95 pivoted as at 7 to bearings 8 rigidly arising from the upper surface of said frames. These levers are formed to embody elongated handle portions 9 and have their opposite ends terminated in rounded edges 10 100 which terminate in substantially straight portions 11, whereby upon the rotation of the levers 6 the same will assume substantially vertical positions in order that their

straight portions 11 will press upon said blocks with sufficient pressure to bind the latter into engagement with the belt ends. Owing to the relation existing between the portions 11 and the pivots 7 of said cam levers the latter will be retained in their vertical positions by the pressure they exercise upon said blocks and will be prevented from unduly rotating so that consequent loss of pressure upon the belt ends will be prevented. Wear plates 12 are carried by the upper surface of the blocks and upon which the pressure ends of the cam levers operate, these plates prevent said levers from wearing grooves in the blocks, and thereby render the operation of the cam levers positive even after extended periods of service.

To draw the frames relatively, use is made of a pair of spaced rods 13. These rods are provided with upper threaded ends 14, which operate within similarly threaded openings 15 formed in the frame 1, whereby upon the rotation of said rods in a specified direction said frame 1 will be moved toward the lower frame 2, as will be clearly understood. The lower ends of the rods 13 are smooth or nonthreaded, and are journaled within bushings 16 carried by the lower frame 2, and to effect the rotation of the rods the extreme lower ends of the latter are equipped with worm gears 17, which mesh with similar and right angularly disposed gears 18 rotatable with a transversely situated actuating shaft 19. This latter shaft is preferably journaled in bearings 20 protruding from the frame 2, and has its ends equipped with crank handles 21, by means of which the shaft may be manually rotated to effect consequent rotation on the part of the rods 13.

From the foregoing description taken in connection with the accompanying sheet of drawings it will be apparent that there is provided a device of considerable utility for the purpose set forth. It is obvious that through the provision of the removable blocks 5 that the frames may be readily attached to the adjoining ends of the belt 3 and that by the mere rotation of the cam levers ample pressure may be applied to said blocks to effect a firm and positive hold of the frames upon said belt. Owing to the dovetail construction of the recesses 4 and the blocks 5 an extremely efficient hold is secured upon the belt ends, as the tendency on part of the belt ends to separate is compensated for by the wedging action on part of the blocks 5. Through the provision of the worm controlled actuating mechanism, the frames may be quickly operated to assume various relative positions, and the use of worm gears in this particular structure is of decided advantage, in view of the fact that the gears permit of the application of

considerable pressure to the frames with but a minimum of physical exertion, and furthermore the tendency of the rods 13 to rotate when under stress is obviated by the locking action of the worm gears. It will thus be apparent that a mechanism has been provided for quickly and securely positioning the frames upon the ends of a belt and that the means are of such character as to prevent the frames from slipping upon said belt when pressure is being applied thereto, and in conclusion effective means are provided for controlling the relative positions of said frames. In the present adaptation of the invention it has been simply found necessary to thread the upper ends of the rods 13 in order that the frames may be drawn together or apart, but it is obvious that the lower portions of said rods may also be threaded to permit of quicker operation on part of the frames without departing from the spirit or intent of the invention.

In order to compensate for belts of different thicknesses, and to render the action of the cam levers positive under all conditions, a plurality of the wear plates 12 are provided. These plates are pivoted upon a common pin 22 and are capable of independent movement, so that when a belt of considerable thickness is carried by the frame, one or more of each set of these plates 12 may be swung to such positions so that they will not engage with the cam levers. This construction has the desirable effect of maintaining the wear plates at a constant level irrespective of the varying thickness of the belts to which the device is attached, and thus renders the clamping mechanism thereof effective and reliable at all times.

What I claim is:

1. In a belt stretcher, a pair of spaced clamping frames arranged to receive the opposed ends of a belt, said frames including upper and lower members between which the belt ends are adapted to be clamped, cam levers for locking the upper members to the lower members pivotally carried by said lower members and arranged upon oscillation to force said upper members into belt holding engagement with the lower members, and a plurality of sets of pivotally mounted plates carried by said upper members, said plates being capable of being selectively positioned beneath said cam levers to receive the wear caused by the latter and to render said levers effective irrespective of belt thicknesses.

2. In a belt stretcher, a pair of spaced clamping frames arranged to receive the opposed ends of a belt, said frames including separable upper and lower members between which the belt ends are arranged to be clamped, cam levers pivotally carried by said lower members and arranged when in

active positions to force said upper members into locked engagement with said lower members, and a plurality of sets of pivotally mounted wear plates carried by said upper members, each of said sets having a common pivot, the latter being so located as to permit said plates to be selectively moved to positions beneath said cam lever, whereby

the wear of said levers may be received by said plates and to permit the levers to be rendered effective irrespective of belt thicknesses, and means for effecting relative movement on the part of said frames.

In testimony whereof I affix my signature.

FRED A. FISHBAUGH.
